[57] CLAIM

The ornamental design for a deck of playing cards, as shown and described.

DESCRIPTION

FIG. 1 is a face side plan view of a first suit of a deck of playing cards showing my new design;

FIG. 2 is a face side plan view of a second suit of the deck of playing cards showing my new design;

FIG. 3 is a face side plan view of a third suit of the deck of playing cards showing my new design;

FIG. 4 is a face side plan view of a fourth suit of the deck of playing cards showing my new design; and,

FIG. 5 is an enlarged face side plan view of Princess, Jack, Queen, and King cards of FIG. 1, wherein broken lines represent a first half portion of personage indicia at each of the respective broken lined areas of FIGS. 1 through 4, wherein a second half portion of personage indicia at each of the broken lined areas is conventionally identical to the first half portion thereof.
